CLAIM

The ornamental design for a display screen or portion thereof with graphical user interface as shown and described.

DESCRIPTION

FIG. 1 is a front view of a first embodiment of a display screen or portion thereof with graphical user interface showing our new design;

FIG. 2 is a front view of a second embodiment of a display screen or portion thereof with graphical user interface showing our new design; and,

FIG. 3 is a front view of a third embodiment of a display screen or portion thereof with graphical user interface showing our new design.

The broken lines show portions of the display screen or portion thereof with graphical user interface that form no part of the claimed design. The dotted lines shown in the figures illustrate the perimeter of a portion of a display screen and form no part of the claimed design.

1 Claim, 3 Drawing Sheets
